UNITED STATES PATENT OFFICE.

JOHN C. HUBINGER, OF KEOKUK, IOWA.

SIGNALING APPARATUS.

No. 825,055.

Specification of Letters Patent.

Patented July 8, 1906.

Application filed September 22, 1905. Serial No. 279,596.

To all whom it may concern:

Be it known that I, JOHN C. HUBINGER, a citizen of the United States, residing at Keokuk, in the county of Lee and State of Iowa, have invented a certain new and useful Improvement in Signaling Apparatus, of which the following is a full, clear, concise, and exact description, reference being had to the accompanying drawings, forming a part of this specification.

My invention relates to signaling apparatus, and particularly to the adjusting mechanism therefor.

More particularly speaking, my invention comprises improved balancing and adjusting means for the armature of signaling or signal-controlling apparatus, such as alternating-current bells and relays, the invention being of particular importance and utility in connection with biased telephone-ringers in which the armature has heretofore been biased by means of spring mechanism. My invention contemplates the use of weights which may be adjustably attached to one side of the armature-pivot or to both sides thereof, so that the armature may be balanced or may be biased in either direction to be selectively responsive to selective currents.

My invention will be best understood by reference to the accompanying drawings, in which—

Figure 1 shows an ordinary polarized telephone-ringer and the application of the adjustable weights to the armature thereof, and Fig. 2 shows a polarized relay and the arrangement of the weights thereon.

The ringer-bell in Fig. 1 is shown as of the ordinary construction comprising the coils 1 and 2, mounted on the cores 3 and 4, connected by the yoke-piece 5. The polarizing-magnet 6 supports the armature-frame 7, to which is pivoted the armature 8 before the poles 9 and 10 of the cores. The tapper-rod 11 terminates in the tapper 12, adapted for engagement with the bells 13 and 14.

From the ends of the armature extend threaded stems 15 and 16, which may be integral with the armature and on which the weights 17 and 18 may be moved longitudinally. Two or more weights are preferably used on each stem, so that they may mutually lock each other in position. If the bell is to be responsive to ordinary alternating current, the weights are adjusted along the

stem to balance the armature, and if the weights 17 and 18 are equal they will be at equal distances from the armature-pivot. If the bell is to be responsive to pulsating current, for instance, of one polarity, the weights 17 will be adjusted correspondingly to give the armature the proper overbalance or bias. The weights 17, for instance, will be moved to the end of the stem 15, and the weights 18 will be moved inwardly toward the armature-body, or if the polarity to which the bell is to respond is of the opposite character the weights 18 will be moved outwardly and the weights 17 inwardly. Any degree of overbalance may thus be accomplished. For the bells near the source of ringing this overbalance will be greater; but for distant bells, where the line resistance is comparatively great, the overbalance may be less to render the device more delicate.

Fig. 2 shows my invention applied to a polarized relay which, like the device of Fig. 1, is of ordinary construction and comprising the same essential parts. The armature in this device, however, is not provided with a tapper-rod, but instead acts as a contact-arm for engagement with the contact 19 for closing a local signal-circuit 20, containing the source 21 and the signaling device 22. As shown, only one set of weights 17 is shown and engaging the stem 15, the armature being thus biased and adapted upon response to current-flow of one character to be actuated to engage the contact 19 to close the local circuit. To cause the device to be responsive to currents of opposite character, the stem 16 only will be provided with weights and the contact 19 associated with the stem 15. As in Fig. 1, both stems 15 and 16 may also be provided with weights which may be relatively adjusted to give the proper bias and adjustment to the armature.

I do not wish to be limited to the adaptation of my invention to the devices shown; nor do I wish to be limited to the exact arrangement thereof, as changes may readily be made without departing from the spirit of the invention.

I claim as new and desire to secure by Letters Patent—

1. In a signal-controlling device, the combination with electromagnet-poles, of an armature subjected to the influence thereof, signaling apparatus controlled by the movements of the armature, and a weight on said

- armature at each side of the pivot thereof, said weights being adapted for movement toward or away from the armature-pivot.
2. In a signal-controlling device, the combination with electromagnet-poles, of an armature subjected to the influence thereof, signaling apparatus controlled by the movements of the armature, and a weight at each end of the armature having secure threaded engagement therewith, said weights being adjustable toward or away from the armature-pivot.
3. In a signal-controlling device, the combination with electromagnet-poles, of an armature subjected to the influence thereof, signaling apparatus controlled by the movements of the armature, a weight at each end of the armature having secure threaded engagement therewith, said weights being adjustable toward or away from the armature-pivot, and means for locking said weights in any adjustable position.
4. In a signal-controlling device, the combination with electromagnet-poles, of an armature subjected to the influence of said poles, signaling apparatus controlled by the movements of said armature, a threaded extension from the armature at one side of its pivot-point, and a weight having threaded engagement with said extension to be adjustable thereon toward or away from the armature-pivot whereby the end of the armature is normally held in engagement with the corresponding pole-face.
5. In a signal-controlling device, the combination with electromagnet-poles, of an armature subjected to the influence thereof, signaling apparatus controlled by the movements of the armature, a threaded extension from the armature at each side of its pivot, a weight having adjustable engagement along each extension whereby the armature may be balanced or unbalanced to be held in engagement with the corresponding pole-face, and means for locking the weights in any adjusted position.
6. In a signal-controlling device, the combination with electromagnet-poles, of an armature pivoted between said poles having its ends overlapping the pole ends, and a weight engaging one end of the armature to normally hold said end against the corresponding pole end.
7. In a signal-controlling device, the combination with electromagnet-poles, of an armature pivoted between said poles having its ends overlapping the pole ends, and a weight adjustable along one end of the armature to hold said end normally in engagement with the corresponding pole end.
8. In a signal-controlling device operated by alternating or pulsating currents, the combination with electromagnet-poles, of a polarized armature pivoted between said poles with its ends overlapping the pole ends, and a weight engaging one end of the armature to normally hold said end against the corresponding pole end, the armature being thereby responsive to current-flow of one polarity only.
9. In a signal-controlling device operated by alternating or pulsating current, the combination with electromagnet-poles, of a polarized armature pivoted between said poles with its ends overlapping the pole ends, and a weight engaging one end of the armature to normally hold said end against the corresponding pole end, the armature being thereby responsive to current-flow of one polarity only, said weight being adjustable along the armature end.
10. In a signal-controlling device operated by alternating or pulsating current, the combination with electromagnet-poles, of a polarized armature pivoted between said poles with its ends overlapping the pole ends, a weight engaging each end of the armature and adjustable thereon whereby one end of the armature is normally held in engagement with the corresponding pole end.
11. In a signal-controlling device operated by alternating or pulsating currents, the combination with electromagnet-poles, of a polarized armature pivoted between said poles with its ends overlapping the pole ends, screw-threaded extensions from the armature ends, a weight for each armature end having engagement with the screw-threaded extension therefrom, said armature being adapted to be overbalanced by said weights so that one end thereof is normally in contact with the corresponding pole end whereby the device is responsive to current-flow in one direction only.
- In witness whereof I hereunto subscribe my name this 14th day of September, A. D. 1905.
